United States Patent Office.

CHARLES F. BUTTERWORTH, OF TROY, NEW YORK.

Letters Patent No. 98,025, dated December 21, 1869.

IMPROVEMENT IN EXPANDING MUFF-BLOCKS.

The Schedule referred to in these Letters Patent and making part of the same.

To all whom it may concern:

Be it known that I, CHARLES F. BUTTERWORTH, of Troy, in the county of Rensselaer, and State of New York, have invented a new and useful Improvement in Extension Muff-Block; and I do hereby declare that the following is a full, clear, and exact description thereof, which will enable others skilled in the art to make and use the same, reference being had to the accompanying drawings, forming part of this specification.

This invention relates to a new and useful improvement in blocks for forming and stretching muffs, in the process of manufacturing that article.

In the accompanying drawings—

Figure 1 represents a longitudinal view of the block partly in section.

Figure 2 is an end view.

Similar letters of reference denote corresponding parts.

A is the main portion of the block, to which the screw-rod is attached, so that it may freely revolve, but have no longitudinal motion.

B is the movable or adjustable portion of the block, through which the screw-rod passes, and which bears the nut which engages with the screw-rod.

C represents the screw-rod. This screw-rod passes entirely through both parts of the block, with its ends square, so that it may be revolved by means of the key D.

E is the screw-nut, which is secured in the end of the part B, as seen in the drawing.

The screw-rod C is secured in the part A by means of the collar F and the plate G.

The block is in form a cylinder, and the part A is hollowed out to receive part B, as seen in the drawing, so that when the part B is extended by turning

the screw, it will move outward on a line corresponding with the surface of A.

One or more dowel-pins may be employed, for preserving a uniform position for the parts, as seen at h.

A band may also be employed to cover the joint between the two parts, as seen at i. This band may be let into the parts, so that the block will present a smooth and even surface.

It will be seen that when the fur skin is sewed up to secure the desired diameter for the muff, and the block inserted, and the muff nailed to the ends thereof, the block may be elongated and the muff stretched to any desired degree of tension, by simply turning the screw.

Strips or pieces of wood may be attached to the parts of the block, for increasing its diameter.

By the use of this block the operation of forming the muff, so as to utilize all the fur skin, is rendered perfectly easy.

Having thus described my invention,

I claim as new, and desire to secure by Letters Patent—

The combination of the two cylindrical blocks A B, one recessed and the other shouldered, as set forth, with the threaded, swivelled, and shouldered shaft C F, plate G, and threaded nut E, and the collar or sleeve i, all of said parts being arranged and brought together in the manner specified, to form an adjustable muff-block.

The above specification of my invention signed by me, this 19th day of August, 1869.

CHARLES F. BUTTERWORTH.
